SWITCH CONTROL AND INDICATION SYSTEM

Henry S. Young, Wilkinsburg, Pa., assignor to The Union Switch & Signal Company, Swissvale, Pa., a corporation of Pennsylvania

Application November 26, 1938, Serial No. 242,535

16 Claims. (Cl. 246—135)

My invention relates to a switch control and indication system, and particularly to improved means for preventing improper operation of the switch.

5. It has heretofore been proposed to provide switch control means incorporating a lever movable between a normal and a reverse position to effect control of the switch so that it will move to a position corresponding to that occupied by 10 the lever. It has also been proposed to provide means such as a signal control lever associated with the switch control lever for controlling signals which control movement of trains through the track stretch in which the switch is mounted. 15. It has been proposed heretofore to have associated with the switch control lever mechanism known as the "quick switch" and operative on movement of the control lever from either of its positions towards the other position to prevent return of the control lever to its initial 20 position unless the switch completes its movement to the other position and effects energization of an indication magnet for such other position of the switch. 25. It is an object of my invention to provide a switch control system in which a stick relay performs the functions heretofore performed by the "quick switch" mechanism.

A further object of my invention is to provide 30 a system of the type described in which neutral switch repeating relays are employed, the system being arranged to prevent undesired energization of either of the indication magnets in the event the energizing circuits for the switch repeating 35 relays become crossed.

Another object of my invention is to provide an improved switch control and indication system.

Other objects of my invention and features of 40 novelty will be apparent from the following description taken in connection with the accompanying drawings.

I shall describe one form of apparatus embodying my invention, together with three modifications which I may employ, and shall then point out the novel features thereof in claims.

45 Referring to the drawings, Fig. 1 is a diagram illustrating one embodiment of the improved switch control and indication system provided by my invention.

50 Fig. 2 is a fragmentary diagram illustrating a modification which I may employ.

Fig. 3 is a fragmentary diagram illustrating another modification which I may employ, and

55 Fig. 4 is a fragmentary diagram illustrating a

further modification of the system provided by my invention.

Referring to Fig. 1 of the drawings, the reference character W identifies a railway track switch which is movable between a normal and a reverse position by suitable power driven means. This power driven means is here shown diagrammatically as a fluid pressure motor which is controlled in the manner well-known in the art by a lock magnet valve device LMV, a normal 10 magnet valve device NMV, and a reverse magnet valve device RMV.

The lock magnet valve device LMV, when energized, permits the supply of fluid under pressure to the motor, while the normal and reverse magnet valve devices NMV and RMV control the supply of fluid under pressure to the motor in such manner as to effect operation of the motor to cause movement of the switch W to the normal or reverse position.

The lock magnet valve device LMV, when de- 15 energized, cuts off the supply of fluid under pressure to the motor and thereby prevents operation of the motor to move the switch.

The supply of current for energizing the mag- 20 net valve devices LMV, NMV and RMV is controlled by a control lever L which may form a part of an interlocking machine. The control lever L is controlled by a normal magnet NM, 25 a reverse magnet RM, and a lock magnet DM. 30

The supply of current for energizing the mag- 35 nets NM and RM is controlled in a manner hereinafter explained in detail by a normal indica- 40 tion relay NKR, a reverse indication relay RKR, a stick relay S, and by contacts associated with 45 the control lever L.

The lock magnet DM is energized by current supplied over a circuit which is controlled by contacts 8 and 9 which are operated by a latch, 40 not shown, associated with the lever L, while this circuit is also controlled in the manner well-known in the art by relays, not shown, responsive to traffic conditions in the vicinity of the switch so that the circuit can be completed only when it is safe to effect a change in the position occupied by the switch W.

The circuits for energizing the normal and reverse indication relays NKR and RKR are controlled by a contact 10 which is movable in accordance with movement of the switch W.

The control lever L is movable about an axis throughout a segment of a circle between normal and reverse points N and R, while intermediate points in the range of movement of the lever L are designated in the drawings by the letters 50 55

X, B, D and Y. The positions B and D are the normal and reverse indication positions of the control lever L.

The lever L has associated therewith a plurality of contacts which are arranged so that the circuits controlled thereby are complete when and only when the lever L is at or between predetermined points in its range of movement. The contacts are shown diagrammatically in the drawings and the positions of the lever L in which the contacts are closed are indicated by the letters identifying the contacts.

The lever L has associated therewith two contacts BD which are closed when the lever L is in any position between the points B and D, or is at either of these positions. The lever L also has associated therewith a contact D which is closed when and only when the lever L is substantially at the position D, while there is a contact B which is closed when and only when the lever L is substantially at the position B.

In addition the lever L has associated therewith a contact NB which is closed when the lever L is in any position between the points N and B, or is at either of these points, while there is a contact RD which is closed when the lever L is in any position between the points R and D, or is at either of these points.

The lever L is mounted on a shaft, not shown, on which are also mounted three segments, one for each of the magnets RM, NM and DM. Each of these magnets has an armature which controls a dog which cooperates with the associated segment to limit or prevent movement of the lever L.

The segment associated with the magnet RM is arranged so that unless the magnet RM is energized the lever L cannot be moved towards the position R farther than the position D.

Similarly, the segment associated with the magnet NM is arranged so that unless the magnet NM is energized the lever L cannot be moved towards the position N farther than the position B.

The segment associated with the magnet RM is also arranged so that the lever L may be freely moved away from the position R even though the magnet RM is deenergized. Likewise, the segment associated with the magnet NM is arranged so that the lever L may be freely moved away from the position N even though the magnet NM is deenergized.

The segment associated with the magnet DM is arranged so that when the magnet DM is deenergized the lever L, if in the position N, cannot be moved farther from this position than the position X, while if the lever L is in the position R, and the magnet DM is deenergized, the lever L cannot be moved farther away from the position R than the position Y.

The details of the construction of the lever L and the associated contacts, segments and cooperating dogs are not a part of this invention, and these portions of this system are the same as the corresponding portions of interlocking machines now in service.

The interlocking machine of which the switch control lever L forms a part includes a signal control lever, not shown, associated with the switch control lever L and controlling the signals for governing movement of trains through the track stretch in which the switch W is located.

The signal control lever has an intermediate position in which all of the signals, not shown, associated with the switch W are at stop, while the lever is movable in one direction from this

intermediate position to effect or permit clearing of selected ones of the signals associated with the switch W, as for example the signals governing movement of trains in one direction across the switch W.

Similarly the signal control lever is movable in the other direction from the intermediate position to effect or permit clearing of other ones of the signals associated with the switch W, as for example the signals governing movement of trains in the other direction across the switch W.

The switch control lever L and the signal control lever, not shown, are mechanically or otherwise interconnected in the manner well known in the art so that the signal control lever may be moved from the intermediate position only when the switch control lever is in the normal position N or the reverse position R, and so that the switch control lever L may be moved only when the signal control lever is in the intermediate position.

The switch operated contact 10 controls connection from terminal B of a battery 12 to the windings of the normal and reverse indication relays NKR and RKR. One terminal of the winding of each of these relays has connected thereto a branch of wire 15 leading from terminal C of battery 12. The other terminal of the winding of relay NKR is connected by wire 16 to contact 18 which is engaged by switch operated contact 10 when and only when the switch W is in the normal position. In this position of the switch W contact 10 also engages a contact 19 to which is connected a branch of wire 20 leading from terminal B of battery 12. Accordingly in the normal position of the switch W a circuit is established to energize the winding of relay NKR, this circuit being traced from terminal B of battery 12 through wire 20, contacts 19, 10 and 18, wire 16, winding of relay NKR, and wire 15 to terminal C of battery 12.

When the switch W is in the reverse position, the contact 10 engages contacts 22 and 24. A branch of wire 20 is connected to contact 22, while contact 24 is connected by wire 25 to one terminal of the winding of relay RKR. When the switch W is in the reverse position, therefore, a circuit is established to energize the winding of relay RKR, this circuit being traced from terminal B of battery 12 through wire 20, contacts 22, 10 and 24, wire 25, winding of relay RKR and wire 15 to terminal C of battery 12.

Although the switch operated contact 10 has been described as being in engagement with the stationary contacts associated therewith when the switch W is in the normal or the reverse position, it is contemplated that the apparatus may be arranged so that the contact 10 will engage the associated stationary contacts only when the switch W has been moved to its normal or reverse position and the operating mechanism for the switch has been conditioned to lock the switch in such position.

The normal indication relay NKR has a movable contact 27 which when released engages a stationary contact 28 to which is connected a branch of wire 20 leading from terminal B of battery 12. The contact 27 is connected by wire 29 to movable contact 30 of reverse indication relay RKR. Contact 30 when released engages a stationary contact 31 which is connected by wire 32 to one terminal of the winding of stick relay S, the other terminal of which has connected thereto a branch of wire 15 leading from terminal C of battery 12. Contact 30 of relay RKR when

picked up engages a stationary contact 34 to which is connected wire 35 leading to a front contact 36 of stick relay S.

The normal indication relay NKR has, in addition, a movable contact 38 which when picked up engages a stationary contact 39 which is connected by a wire 40 to front contact 41 of stick relay S.

Contact 38 of relay NKR is connected by wire 42 to movable contact 44 of relay RKR, while contact 44 when released engages stationary contact 45 to which is connected a branch of wire 20 leading from terminal B of battery 12.

The contact 38 of relay NKR when released engages a stationary contact 47 to which is connected wire 48 leading to one terminal of the lock magnet valve device LMV.

The stick relay S has a movable contact 50 which when picked up engages a stationary contact 51 to which is connected a branch of wire 32 leading to one terminal of the winding of the relay. The contact 50 has connected thereto a wire 53, while contact BD associated with the lever L controls a circuit from wire 20 to wire 53.

It will be seen that when the contact BD is closed and contact 50 is picked up, a stick circuit is established for the winding of relay S, this circuit being traced from terminal B of battery 12 through wire 20, lever contact BD, wire 53, contacts 50—51 of relay S, winding of relay S, and wire 15 to terminal C of battery 12.

The stick relay S has, in addition, a contact 55 which when picked up engages contact 36. Contact 55 has connected thereto a wire 57, while lever operated contact D controls connection between wire 57 and one terminal of the winding of reverse indication magnet RM, the other terminal of which has connected thereto a branch of wire 15 leading from terminal C of battery 12.

The stick relay S also has a movable contact 58 which when picked up engages a stationary contact 41, while contact 58 has connected thereto a wire 60. Lever operated contact B controls connection from wire 60 to one terminal of the normal indication magnet NM, the other terminal of which has connected thereto a branch of wire 15 leading from terminal C of battery 12.

The lever operated contact NB controls connection from wire 20, leading from terminal B of battery 12, to wire 62 leading to one terminal of the winding of the normal magnet valve device NMV, while lever operated contact RD controls connection between wire 20 and wire 64 leading to one terminal of the winding of reverse magnet valve device RMV. Similarly lever operated contact BD controls connection from wire 20 to wire 48 leading to the lock magnet valve device LMV. The other terminal of the winding of each of the magnet valve devices is constantly connected to a branch of wire 15 leading from terminal C of battery 12.

The equipment is shown in Fig. 1 of the drawings in the position which it assumes when the switch W and the control lever L are in their normal positions. At this time contact 10 establishes the circuit for energizing the winding of the normal indication relay NKR, while the circuit of the winding of the reverse indication relay RKR is interrupted. As contact 27 of relay NKR is picked up, the pick-up circuit for the stick relay S is interrupted, and as contact 50 of relay S is released, the stick circuit for the relay winding is interrupted. The stick circuit is also interrupted by contact BD associated with lever

L since contact BD is open when the lever L is in the normal position, that is position N.

In addition at this time the circuit of the winding of the lock magnet valve device LMV is interrupted since contact BD controlling the circuit to wire 48 is open, and since contact 38 of relay NKR is picked up. As the lock magnet valve device LMV is deenergized, the supply of fluid under pressure to the switch motor is cut off and the switch, therefore, cannot be moved.

At this time, since the lever L is in the position N, contact NB is closed and a circuit is established from wire 20 to wire 62 leading to the normal magnet valve device NMV with the result that the winding of this device is energized. However, since the lock magnet valve device LMV is deenergized at this time, energization of the normal magnet valve device NMV is without effect, but is maintained to restore the switch to normal in event of creepage as explained later.

It is assumed at this time that the latch operated contacts 8 and 9 controlling the circuit of the winding of the lock magnet DM are open with the result that the winding of magnet DM is deenergized.

In addition, at this time the windings of the magnets NM and RM are interrupted by the lever operated contacts D and B, and also by the contacts of the stick relay S.

If at this time the operator wishes to effect movement of the switch W from the normal to the reverse position, he may do so by moving the lever L from the normal position N to the reverse indicating position indicated at D.

As explained above, the signal control lever, not shown, and the switch control lever L are interconnected in such manner that the switch control lever can be moved to effect movement of the switch only when the signal control lever is in its intermediate position, at which time all of the signals controlled thereby are conditioned to display the stop indication.

In order to effect movement of the lever, it is necessary first to close the latch contacts 8 and 9, thereby energizing the lock magnet DM. As previously explained, the circuit of the winding of the lock magnet DM is controlled not only by the latch contacts 8 and 9, but also by relays, not shown, responsive to traffic conditions in the vicinity of the switch W so that the circuit of the winding of the lock magnet DM can only be completed if it is safe to effect movement of the switch W. Assuming that the circuit of the winding of the lock magnet DM is completed by closing of contacts 8 and 9, this winding becomes energized and the dog controlled thereby is released to permit movement of the lever L past the position X and to the reverse indicating position D, while further movement of the lever L is prevented by the dog controlled by the armature of the reverse indication magnet RM.

On movement of the lever L out of the zone NB, the previously traced circuit to the normal magnet valve device NMV is interrupted, while on movement of the lever L to the zone intermediate the points B and D, the contact BD completes the circuit for energizing the lock magnet valve device LMV. On movement of the lever L to the position D, at which point further movement of the lever is restrained by the dog associated with the reverse indication magnet RM, the contact RD completes the circuit from wire 20 to wire 64 leading to the winding of the reverse magnet valve device RMV.

On energization of the reverse magnet valve

device RMV, fluid under pressure is supplied to the motor to cause the motor to move the switch W away from the normal position to the reverse position. On movement of the switch W away from the normal position, contact 10 is moved out of engagement with contacts 18 and 19, thereby interrupting the circuit for energizing the normal indication relay NKR with the result that the contacts of this relay become released. 5

10 On release of contact 38 of relay NKR, a circuit is established to maintain the lock magnet valve device LMV energized. This circuit is traced from terminal B of battery 12 through wire 20, contacts 45—44 of relay RKR, wire 42, contacts 15 38—47 of relay NKR, wire 48, winding of lock magnet valve device LMV and wire 15 leading to terminal C of battery 12. The lock magnet valve device LMV, therefore, will remain energized to permit the supply of fluid under pressure to the motor as long as both of the indication relays are deenergized. 20

On release of contact 27 of relay NKR, it engages contact 28 and completes the pick-up circuit for the stick relay S. This circuit is traced from terminal B of battery 12 through wire 20, contacts 28—27 of relay NKR, wire 29, contacts 25 30—31 of relay RKR, wire 32, winding of relay S and wire 15 to terminal C of battery 12. 30

On energization of the winding of relay S, its contacts become picked up and its contact 50 establishes the stick circuit for the relay winding. This circuit includes wire 20 leading from terminal B of battery 12, contact BD of lever L, wire 53, contacts 50—51 of relay S and wire 32 to one terminal of the relay winding. It will be seen, therefore, that on energization of the winding of relay S, a stick circuit is established to maintain the relay winding energized as long as the lever L remains in the zone BD and contact BD remains closed. On movement of lever L 40 outside of the zone BD, contact BD becomes opened and the stick circuit for the relay winding is interrupted. 45

On picking up of the contacts of the stick relay S, contact 55 engages contact 36 to establish a circuit for energizing the winding of the reverse indication magnet RM. This circuit, however, does not become complete until contact 30 of relay RKR is picked up. 50

When the switch W reaches the reverse position, contact 10 is moved into engagement with contacts 22 and 24, thereby completing the energizing circuit for the winding of relay RKR, and on energization of this winding, contact 30 of the relay is picked up and completes the circuit 55 for energizing the winding of reverse indication magnet RM. In addition, on energization of the winding of relay RKR, contact 44 is picked up, thereby interrupting the circuit for establishing connection from wire 20 to wire 48 leading to the lock magnet valve device LMV. 60

Furthermore, on picking up of contact 30 of relay RKR, the pick-up circuit of the stick relay S is interrupted, but at this time the winding of relay S remains energized by current supplied over the stick circuit established by contact 50 of the relay. 65

When the contacts of relay S are picked up at a time when relay RKR is energized, relay NKR is deenergized, and lever L is at position D, 70 a circuit is established for energizing the reverse indication magnet RM. This circuit is traced from terminal B of battery 12 through wire 20, contacts 28—27 of relay NKR, wire 29, contacts 30—34 of relay RKR, wire 35, contacts 36—55 75 of relay S, wire 51, lever operated contact D,

winding of reverse indication magnet RM, and wire 15 to terminal C of battery 12. 5

On energization of the winding of reverse indication magnet RM, the dog operated by the armature of this magnet is released to permit movement of the lever L past the position D and all of the way to the position R. 10

On movement of the lever L away from the reverse indication position D towards the position R, contact D operated by the lever becomes opened, thereby interrupting the circuit of the winding of reverse indication magnet RM. However, before contact D is opened the lever L will have been moved far enough to prevent reengagement of the dog with the shoulder on the segment associated with the magnet RM, and hence lever L may be moved all of the way to the position R. 15

On movement of the lever L to the right from position D, contact BD becomes opened, thereby interrupting the stick circuit for the winding of relay S with the result that the contacts of relay S become released. At this time the pick-up circuit for the winding of relay S is interrupted since contact 30 of relay RKR is picked up, while on release of the contacts of relay S, contact 50 further interrupts the stick circuit for the relay winding with the result that subsequent reclosing of the contact BD will not effect picking up of the stick relay contacts. 20 30

In addition, on movement of the lever L out of the zone between the positions B and D, the contact BD controlling the circuit of the lock magnet valve device LMV is opened, and the winding of the lock magnet valve is deenergized 35 with the result that the lock magnet valve cuts off the supply of fluid under pressure to the motor for operating the switch W. 40

However, as the switch W has already been moved to the reverse position, fluid under pressure is no longer required by the motor for operating the switch, and deenergization of the lock magnet valve device serves to prevent undesired movement of the switch. 45

After the lever L has been moved all of the way to the position R, the operator releases the latch and contacts 8 and 9 interrupt the circuit of the lock magnet DM and the dog associated with this magnet serves to prevent undesired movement of the lever L away from the position R. 50

It will be seen that when the lever L is in the position R, contact RD controlling the circuit of the winding of the reverse magnet valve device RMV is closed with the result that the winding of the valve device RMV remains energized. 55

However, as the lock magnet valve device LMV is normally deenergized at this time, energization of the reverse magnet valve device is without effect, but the energization is maintained for the purpose of restoring the switch to the full reverse position in event of creepage as explained later. 60

When the lever L is in the reverse position R the signal control lever, not shown, associated with the lever L may be actuated to establish circuits to permit clearing of the proper signals and thus permit such train movements across the switch W as may be carried out when the switch W is in the reverse position. 65

The system operates in a manner similar to that just described if with the switch in the reverse position the operator desires to effect movement thereof to the normal position. 70

As previously explained, the signal control lever and the switch control lever L are inter- 75

connected in such manner that the switch control lever can be moved to effect movement of the switch only when the signal control lever is in its intermediate position, at which time all 5 of the signals controlled thereby are conditioned to display the stop indication.

In order to effect movement of the switch, the operator first closes the latch contacts 8 and 9 to energize the lock magnet DM to permit movement of the lever L away from the position R. The lever L may then be moved from position R to the normal indication position B where further movement of the lever is prevented by the dog and segment associated with the normal indication magnet NM.

On movement of the control lever L out of the zone RD, contact RD becomes opened, thereby interrupting the circuit of the reverse magnet valve device RMV. On movement of the control lever 20 L to the zone BD, contact BD becomes closed and establishes the circuit for energizing the lock magnet valve device LMV, while on movement of the lever L to the normal indication position B, contact NB is closed and establishes the circuit 25 for the normal magnet valve device NMV. When the lever L is in the position B, therefore, magnet valve devices NMV and LMV are both energized and fluid under pressure is supplied to the motor for the switch W to effect movement of the 30 switch from the reverse to the normal position.

On movement of the switch W away from the reverse position, contact 10 moves out of engagement with contacts 22 and 24, thereby interrupting the circuit of the winding of relay RKR with 35 the result that its contacts become released. At this time contact 27 of relay NKR is released so that on release of contact 30 of relay RKR, the pick-up circuit for the winding of relay S is complete and the contacts of relay S become 40 picked up. On picking up of contact 50 of relay S at a time when lever L is in the zone BD, the stick circuit for the winding of relay S is established so that the contacts of relay S remain picked up after picking up of contact 27 of relay 45 NKR.

When the switch W completes its movement to the normal position, contact 10 engages contacts 18 and 19, thereby completing the circuit for energizing the winding of relay NKR. The contacts of relay NKR, therefore, become picked up and contact 27 is opened to interrupt the pick-up circuit for the stick relay S, while contact 38 of relay NKR becomes picked up to establish the circuit for energizing the normal indication magnet NM. This circuit includes wire 20, contacts 45-44 of relay RKR, wire 42, contacts 38-39 of relay NKR, wire 40, contacts 41-59 of relay S, wire 60, lever operated contact B, winding of normal indication magnet NM, and wire 15 to 50 terminal B of battery 12.

On energization of the magnet NM, the dog controlled thereby is released to permit movement of the lever L to the position N. On movement of the lever L to the left of position B, contact B 55 is opened and interrupts the circuit of the winding of magnet NM, but before contact B is opened the lever L will have been moved far enough so that further movement of the lever will not be interfered with by the dog associated with the 60 magnet NM.

When the lever L is moved to the left from the normal indication position B, the contacts BD are opened, thereby interrupting the stick circuit of the stick relay S and also interrupting the 75 energizing circuit for the lock magnet valve device

LMV. When the lever L is moved all of the way to the position N, the operator releases the latch and permits the latch operated contacts 8 and 9 to separate, thereby deenergizing the winding of the lock magnet DM.

As previously pointed out on movement of lever L to the normal position N, the signal control lever, not shown, associated with the lever L may be actuated to establish circuits to permit clearing of the proper signals and thus permit such 10 train movements across the switch W as may be carried out when the switch W is in the normal position.

The control system provided by my invention is arranged so that when the switch W is in either 15 position, if the switch should creep from that position, fluid under pressure will be supplied to the motor to return the switch to the position which it should occupy.

When the switch W is in the normal position, 20 the lever L is also in the normal position and contact ND completes the circuit to the normal magnet valve device NMV. At this time, however, contact BD is open and the circuit of the lock magnet valve device LMV is interrupted with the 25 result that no fluid under pressure is supplied to the motor.

When the switch W is in the normal position, contact 10 engages contacts 18 and 19 to maintain the normal indication relay NKR energized, 30 while relay RKR is deenergized.

If the switch W creeps from the normal position, contact 10 is moved out of engagement with contacts 18 and 19, thereby interrupting the energizing circuit for the winding of normal 35 indication relay NKR. On release of contact 38 of relay NKR, a circuit is established to energize the lock magnet valve device LMV. This circuit is traced from wire 20 leading from terminal B of battery 12 through contacts 45-44 40 of relay RKR, wire 42, contacts 38-47 of relay NKR, wire 48 to one terminal of the winding of lock magnet valve device LMV and wire 15 to terminal C of battery 12.

As magnet valve device LMV is now energized, 45 fluid under pressure is supplied to the motor W to effect return of the switch W to the normal position. When the switch reaches the normal position, contact 10 again engages contacts 18 and 19 and establishes the circuit for the winding of relay NKR. On energization of the winding of relay NKR, contact 38 becomes picked up and interrupts the circuit for energizing the winding of lock magnet valve device LMV with the result that this valve device operates to cut 50 off further supply of fluid under pressure to the motor for operating switch W.

The system operates in a similar manner if the switch W creeps from the reverse position. When the switch W is in the reverse position, 60 control lever L is at position R and contact RD is closed with the result that reverse magnet valve device RMV is energized. At this time, however, lock magnet valve device LMV is deenergized, while relay RKR is energized and relay 65 NKR is deenergized.

When the switch W creeps from the reverse position, contact 10 no longer engages contacts 22 and 24, thereby interrupting the circuit for energizing the winding of relay RKR with the result 70 that contact 44 of this relay becomes released and establishes the previously traced circuit for energizing the lock magnet valve device LMV.

On energization of lock magnet valve device LMV at a time when reverse magnet valve de- 75

vice RMV is energized, fluid under pressure is supplied to the motor for the switch W to return the switch W to the reverse position. When the switch W attains the reverse position, contact 10 again engages contacts 22 and 24 and relay RKR becomes energized, while its contact 44 is picked up and interrupts the circuit for energizing lock magnet valve device LMV.

The control system provided by this invention 10 is arranged so that if the wires for energizing the normal and reverse indication relays NKR and RKR should become crossed so that both relays are energized at a time when only one should be, the normal and reverse indication 15 magnets NM and RM cannot be energized, and hence the control lever L cannot be moved all of the way from its normal or reverse position to the other.

This feature of the system prevents clearing 20 of the signals controlled by the lever L, while inability of the operator to complete movement of the lever L to either its normal or reverse position will indicate to the operator that the equipment is not functioning properly.

When the switch W is being moved from the reverse to the normal position, the normal indication magnet NM should become energized to permit movement of the control lever L to the left beyond the position B. The circuit for energizing the normal indication magnet NM is controlled by both indication relays as well as by a contact of the stick relay S, and is complete only when the contact 38 of relay NKR is picked up and contact 44 of relay RKR is released. Relay 30 NKR is normally energized when the switch W is in its normal position, while relay RKR should be deenergized at this time. When the equipment is functioning in the intended manner, therefore, the circuit of the winding of normal indication magnet NM is complete when the lever L is at position B, and the lever L may then be moved to the left from position B to position N.

If, however, on movement of the switch W to the normal position, the wires for energizing 45 the relays NKR and RKR become crossed so that both of these relays are energized, or if the winding of relay RKR is improperly energized by current supplied from any other source, the circuit for energizing the winding of normal magnet NM will be interrupted since contact 44 of relay RKR is picked up.

Accordingly the winding of normal indication magnet NM cannot be energized, and the dog associated with this magnet will prevent 50 movement of the lever L beyond the position B towards the position N. As long as relays NKR and RKR are both energized, therefore, the winding of normal indication magnet NM cannot be energized, and as long as normal indication magnet NM cannot be energized, movement of the lever L to the normal position N cannot be completed. Accordingly, the signal control lever, not shown, associated with the lever L cannot be operated 55 to effect clearing of the signals controlled thereby, while inability of the operator to move the lever L to the normal position will indicate to him that the equipment is not functioning properly.

The equipment operates in a similar manner 70 to prevent movement of the control lever L to the reverse position if both the relays RKR and NKR are energized at a time when the switch W is in the reverse position.

75 Thus it will be seen that the circuit for ener-

gizing the reverse indication magnet RM is controlled by a contact of the reverse indication relay RKR and also by a contact of the normal indication relay NKR.

When the equipment is functioning as intended on movement of the switch W to the reverse position, the relay RKR becomes energized and its contact 30 will be picked up, while relay NKR is deenergized and its contact 27 is released. Under these conditions a circuit is established to permit energization of the winding of reverse indication magnet RM when the stick relay S is energized and the lever L is at position D.

On energization of reverse indication magnet 15 RM, the dog controlled thereby is released and the lever L may be moved from position D to position R.

If, however, on movement of the switch W to the reverse position relay NKR as well as 20 relay RKR is energized due to a cross between the wires leading to the windings of these relays, or if relay NKR is energized from any other source, the circuit for the winding of reverse indication magnet RM cannot be completed and 25 this magnet will remain deenergized. This will be true since contact 27 of relay NKR will be picked up, thus interrupting the circuit of the reverse indication magnet RM.

Accordingly since the winding of reverse indication magnet RM cannot be energized, this magnet will prevent movement of the control lever L to the right beyond position D, and the operator will be unable to complete movement of the lever L to the position R.

The system provided by this invention is also arranged so that if for any reason, such as a crossed wire leading to the winding of one of the indication relays, one or both of the indication relays NKR and RKR fails to become deenergized 40 during movement of the switch W from one of its positions to the other, the normal and reverse indication magnets NM and RM cannot be energized, and hence movement of the lever L to either of its positions N or R cannot be completed.

When the switch W is moved away from either the normal or the reverse position, contact 10 is moved out of engagement with the stationary contacts associated therewith and the circuits for energizing both indication relays are interrupted until the switch W completes its movement to the other of its positions. During movement of the switch W between its two positions, therefore, both of the indication relays NKR and RKR should be deenergized.

When the indication relays NKR and RKR are both deenergized, the pick-up circuit for the stick relay S is established, while on movement of the lever L to the region between positions B and D, contact BD is closed, thereby completing the stick 60 circuit for the relay S with the result that when the contacts of relay S become picked up they remain picked up.

On picking up of the contacts of relay S, contact 55 is closed to permit the circuit of the winding of reverse indication magnet RM to be completed, while contact 58 is closed to permit the circuit of the winding of normal indication magnet NM to be completed.

If the equipment does not function in the intended manner, however, and if both of the indication relays NKR and RKR do not become deenergized during movement of the switch W between its two positions, the stick relay S will not become energized and its contacts will not become closed. 75

Thus it will be seen that if either relay NKR or relay RKR remains energized, the pick-up circuit for relay S is not established and the contact 50 of this relay remains released with the result that 5 the stick circuit for the relay winding cannot be established even though contact BD is closed.

Accordingly, under such circumstances, the contacts 55 and 58 of the relay S remain open and the windings of the reverse indication magnet RM and of the normal indication magnet NM 10 cannot be energized, and hence these magnets operate to restrict movement of the lever L and prevent it being moved either to the position N or to the position R. As previously stated, this 15 inability of the operator to complete movement of the switch control lever L indicates to him that the system is not functioning in the intended manner, while since the lever L cannot be moved to its normal or reverse position the signal control 20 lever cannot be moved out of its intermediate position.

From the foregoing, it will be seen that the stick relay S performs the function of the quick switch, that is, on movement of the lever L from either 25 the normal or the reverse position, the relay S requires operation of the switch in response to this lever movement before movement of the lever to the other position can be completed, or before the lever can be returned to its initial position. 30 Thus it will be seen that the stick relay S is normally deenergized and becomes energized only when the contacts of both indication relays are released. The contacts of both indication relays are released only when the switch W is in transit 35 between its two positions, and, accordingly, in order for the relay S to become energized the switch W must move away from either the normal or the reverse position to an intermediate position.

40 If for any reason on movement of the lever L away from either of its positions to effect movement of the switch W to the other of its positions the switch fails to move, the relays NKR and RKR will not both be deenergized and the relay S 45 will not become energized. As relay S does not become energized under these circumstances, its contacts 55 and 58 remain released and interrupt the circuits of the windings of the normal and reverse indication magnets NM and RM so that 50 neither of these magnets can be energized.

55 Unless one of these magnets is energized, the lever L cannot be moved out of the zone between the points B and D. Hence on movement of the lever L to this zone, the lever cannot thereafter 60 be returned to the position from which it was moved, nor can it complete its movement to the other position unless the switch W moves in response to movement of the lever L and effects deenergization of both of the indication relays.

65 Since operation of the switch W must follow movement of the lever L to prevent locking of lever L in an intermediate zone, and since the indication magnets can only be energized in the event such movement of the switch does occur, the system insures that when an indication is received, that is, when one of the indication magnets is energized and permits movement of the control lever out of the intermediate zone to either its normal or reverse position, that there is correspondence 70 between the position occupied by the switch and the position of the control lever.

In Fig. 2 of the drawings, I have shown a modification of the system shown in Fig. 1 which I may employ and which provides further protection 75 against improper operation of the system

by preventing energization of the lock magnet DM, and, therefore, preventing movement of the control lever L away from either its normal or reverse position unless the positions of the control lever and of the switch are in agreement.

The system shown in Fig. 2 of the drawings is the same as that shown in Fig. 1 of the drawings except as hereinafter explained in detail.

Referring to Fig. 2 of the drawings, it will be seen that the circuit of the winding of the lock magnet DM is controlled not only by the latch contacts 8 and 9 but also by the contacts NX and RY associated with the lever L, and by contacts of the indication relays NKR and RKR.

One terminal of the winding of the lock magnet 15 DM is connected to wire 20 by a circuit controlled by latch contacts 8 and 9, while the other terminal of the winding of the lock magnet DM is connected by a wire 70 to lever controlled contacts NX and RY.

The contact NX is controlled by the lever L in such a manner that the contact is closed when and only when the lever L is in a zone intermediate the positions N and X or is at either of these positions, while contact RY is controlled by the 25 lever L in such a manner that it is closed when and only when the lever L is in a zone intermediate the positions R and Y or is at either of these positions.

The contact NX is connected by a wire 30 with a front contact 72 of relay NKR, while contact RY is connected by a wire 74 with front contact 75 of relay RKR. Relay RKR has a movable contact 76 which is connected by a wire 77 to movable contact 79 of relay NKR.

Contact 76 of relay RKR is adapted when released to engage a stationary contact 80 to which is connected a branch of wire 81, while contact 79 of relay NKR is adapted when released to engage a stationary contact 83 to which is connected another branch of wire 81.

Wire 81 is connected to one terminal of a suitable source of current, such as the battery 12 in the system shown in Fig. 1 of the drawings. The circuit of the wire 81 may be controlled by means 45 well-known in the art, such as lock relays, not shown, responsive to traffic conditions in the vicinity of the switch W, so that the circuit of this wire is complete when and only when it is safe to effect movement of the switch W between its 50 two positions.

In the operation of the system shown in Fig. 2 of the drawings the circuit of the winding of the lock magnet DM can be completed only when one of the indication relays is energized and the other 55 of these relays is deenergized. Thus it will be seen that when relay NKR is energized, its contact 79 is picked up and engages stationary contact 72, while when relay RKR is deenergized, its contact 76 is released and engages stationary contact 80 60 to which is connected wire 81 leading from one terminal of the source of current. A circuit, therefore, is established between wire 81 and wire 70, this circuit including contacts 80-76 of relay RKR, wire 77, contacts 79-72 of relay NKR, wire 65 71, lever controlled contact NX and wire 70 leading to the winding of the lock magnet DM.

When the switch W is in the normal position and the control lever L is in its normal position, the relay NKR is energized and the relay RKR 70 is deenergized and the contacts of the relays NKR and RKR together with lever controlled contact NX permit the circuit to the winding of the lock magnet DM to be completed, and this winding may be energized at this time by clos- 75

- ing the latch contacts 8 and 9, providing that the contacts of the lock relays, not shown, in the circuit of the wire 81 are closed. On energization of the lock magnet DM, the dog controlled by the armature of this magnet is released to permit movement of the lever L away from the position N, and when the lever L is moved beyond the position X, the contact NX is opened, thereby interrupting the circuit for energizing the winding of the lock magnet. However, before the winding becomes deenergized lever L will have been moved far enough so that the segment and dog associated with the lock magnet DM will not interfere with further movement of the lever L.
- 15 In like manner, when the switch W is in the reverse position, the contacts of the normal and reverse indication relays establish a circuit to permit energization of the winding of the lock magnet DM providing the control lever L is in the reverse position.
- When the switch W is in the reverse position, relay RKR is normally energized and relay NKR is deenergized. Accordingly contact 79 of relay NKR is released and engages contact 83, while contact 76 of relay RKR is picked up and engages contact 75. If at this time the control lever L is in the reverse position, contact RY is closed and a circuit is established from wire 81 to wire 70, this circuit being traced from wire 81 through contacts 83-79 of relay NKR, wire 77, contacts 76-75 of relay RKR, wire 74, contact RY and wire 70.
- If at this time it is desired to effect movement of the control lever L away from position R the latch contacts 8 and 9 are closed, and if the contacts of the locking relays, not shown, are closed, the winding of lock magnet DM will be energized and the control lever L may be moved away from the position R. On movement of the control lever L beyond the position Y, contact RY becomes open, but before this occurs the lever will have been moved far enough so that the dog and segment associated with the lock magnet DM will not interfere with further movement of the lever.
- From the foregoing it is clear that the modification shown in Fig. 2 of the drawings operates in such manner that if the normal and reverse indication relays NKR and RKR are energized in the proper manner, the lock magnet DM may be energized to permit movement of the control lever away from either its normal or reverse position.
- This system also operates so that if for any reason the indication relays NKR and RKR are not properly energized, the lock magnet DM cannot be energized, and hence the control lever L cannot be moved away from either its normal or reverse position.
- 60 Thus it will be seen that the circuit of the winding of the lock magnet DM is controlled by contacts of both of the indication relays, and also by contacts controlled by the lever, and the circuits are arranged so that the circuit of the lock magnet winding is complete when and only when there is correspondence between the position of the control lever and the switch, and when the indication relays are properly energized.
- If for any reason both of the indication relays NKR and RKR should be deenergized or both should be energized, no connection would be established between wire 81 and wire 70. Hence the winding of lock magnet DM could not be energized and the lock magnet would not permit

movement of the control lever L away from either the normal or the reverse position.

Similarly, if one of the indication relays is energized and the other is deenergized, a circuit will be established from the wire 81 to one of the wires 71 or 74. However, if at this time the positions of the control lever and the switch are not in correspondence so that the contact NX is closed at a time when relay NKR is released and relay RKR is picked up, or if contact RY is closed at a time when relay RKR is deenergized and relay NKR is energized, no circuit can be established to energize the winding of the lock magnet DM.

From the foregoing it is clear that unless the equipment is operating in the intended manner, the winding of the lock magnet DM cannot be energized and movement of the control lever will be prevented.

In Fig. 3 of the drawings there is shown a modification in which the indication magnets NMA and RMA perform the functions performed by the lock magnet DM in the systems shown in Figs. 1 and 2 of the drawings.

With the modification shown in Fig. 3 of the drawings somewhat differently shaped segments are employed with the indication magnets than are employed in the system shown in Fig. 1. In the system shown in Fig. 3 the segment associated with the normal indication magnet NMA is arranged so that movement of the lever L to the position N and also away from this position is prevented unless the magnet winding is energized.

Similarly in the system shown in Fig. 3 the segment associated with reverse indication magnet RMA is arranged so that movement of the lever L to the reverse position R and also away from that position is prevented unless the winding of the magnet is energized.

The system shown in Fig. 3 is the same as that shown in Fig. 1 except as hereinafter explained in detail.

In the system shown in Fig. 3 of the drawings, as in the system shown in Fig. 1, circuits controlled by the stick relay S and by contacts B and D associated with the control lever L are provided for energizing the normal and reverse indication magnets to permit movement of the lever to the normal or to the reverse position.

The system shown in Fig. 3 of the drawings includes, in addition, circuits controlled by the normal and reverse indication relays, the latch controlled contacts and the lever controlled contacts as well as by contacts of the locking relays, not shown, for energizing the indication magnets to permit movement of the lever L away from either the normal or the reverse positions.

The circuits including the wires 57a and 60a for energizing the reverse magnet RMA and normal magnet NMA are the same as described in detail in connection with the system shown in Fig. 1 of the drawings, and the description of the operation of this portion of the system shown in Fig. 3 need not be repeated.

The circuits shown in Fig. 3 of the drawings are similar to those shown in Fig. 2 and operate so that neither of the indication magnets can be energized unless the positions of the control lever L and the switch W are in correspondence, and unless the indication relays are functioning in the intended manner.

When the switch W is in the normal position, relay NKR should be energized and relay RKR should be deenergized. Under these circum-

stances, assuming that the contacts of the route or locking relays, not shown, controlling the circuit of wire 81a are closed, and that the lever L is in the normal position N so that contact NX 5 is closed, a circuit for energizing the normal indication magnet NMA is established by closing the latch contacts 8a and 9a. This circuit is traced from wire 81a, leading from one terminal of a source of current, through contacts 80a—76a of 10 relay RKR, wire 71a, contacts 79a—72a of relay NKR, wire 71a, latch contacts 9a—8a, lever controlled contact NX, winding of normal indication magnet NMA and wire 15 to the other terminal of the source of current.

15 On energization of the winding NMA, the armature of this magnet is operated to release the dog controlled thereby so that the lever L may be moved away from the normal position.

When the lever L is moved beyond the position 20 X, the contact NX becomes open, thereby interrupting the circuit of the winding of the magnet NMA, but before this winding is de-energized the lever will have been moved far enough so that the dog and segment associated 25 with the magnet NMA will not prevent further movement of the lever L towards the reverse position.

On movement of the lever L to the position D, a circuit is established to energize the winding 30 of the reverse magnet RMA, this circuit being controlled by a contact of the stick relay S and being complete only if the contacts of the stick relay are picked up.

If on movement of the control lever L to the 35 position D the winding of reverse indication magnet RMA becomes energized, the lever may be moved all of the way to the reverse position.

When the lever L is moved beyond the position D, contact BD interrupts the stick circuit of the 40 stick relay S (see Fig. 1) with the result that the contacts of this relay become released and interrupt the energizing circuit of the reverse indication magnet RMA.

However, before the contact BD is opened to 45 effect deenergization of the reverse indication magnet RMA the lever L will have been moved far enough towards the position R so that further movement of the lever in this direction is not prevented by the reverse indication magnet and 50 its associated segment and dog.

The system operates in a similar manner when the lever L is being moved from the reverse position R to the normal position N.

In order to effect movement of the lever L 55 away from the reverse position R it is necessary first to effect energization of the reverse indication magnet RMA. This can be accomplished if the reverse indication relay RKR is energized and the normal indication relay NKR is deenergized 60 as they should be when the switch W is in the reverse position. Under these circumstances, providing the contacts of the locking relays, not shown, are closed, on closing of the latch contacts 8b and 9b a circuit is established for energizing the winding of the reverse indication magnet RMA, this circuit being traced from wire 81a through contacts 83a—79a of relay NKR, wire 71a, contacts 76a—75a of relay RKR, wire 74a, contacts 9b—8b, lever controlled contact RY, and 70 winding of reverse indication magnet RMA to wire 15.

On energization of the winding of the magnet RMA, the lever L may be moved away from the position R into the zone DB, and on movement of 75 the lever to this zone, contact RY becomes opened,

thereby interrupting the circuit of the winding of the magnet RMA. However, before this occurs the lever will have been moved far enough so that further movement of the lever is not restricted by the magnet RMA. 5

On movement of the lever L to the position B, contact NB is closed (see Fig. 1), and the normal magnet valve device NMV is energized to effect the supply of fluid under pressure to the motor for operating the switch W to effect movement 10 of the switch to the normal position.

On movement of the switch W to an intermediate position, the pick-up circuit for the stick relay S (see Fig. 1) is established, and on picking up of the contacts of relay S while the lever 15 L is at position B the stick circuit for the winding of relay S is established. In addition, on picking up of the contacts of relay S at a time when the lever L is at position B, the circuit for energizing the winding of the normal indication magnet 20 NMA is complete and on energization of the winding of this magnet, its armature moves the dog associated therewith so that the lever L may be moved all of the way to the normal position N.

On movement of the lever L to the position N, 25 contact BD is opened (see Fig. 1), thereby interrupting the stick circuit for the winding of relay S and effecting deenergization of the winding of normal indication magnet NMA.

In the system shown in Fig. 3 the circuit for 30 energizing either of the indication magnets can only be established if there is agreement between the position of the switch W and the position of the lever L, and if the indication relays are functioning properly.

Thus, when the lever L is in the normal position, at which time contact NX is closed and contact RY is open, a circuit for energizing the normal indication magnet NMA can be established if and only if the normal indication relay NKR is 40 energized and the reverse indication relay RKR is deenergized.

If for any reason both indication relays NKR and RKR are energized or both are deenergized, or if when the lever L is in the normal position 45 relay RKR is energized and relay NKR is deenergized, the circuit of the winding of the normal indication magnet NMA cannot be completed, and this magnet will prevent movement of the lever L away from the normal position. 50

Similarly, if when the lever L is in the reverse position, at which time contact RY is closed and contact NX is open, a circuit for energizing the reverse indication magnet RMA can be established if and only if the reverse indication relay 55 RKR is energized and the normal indication relay NKR is deenergized.

If for any reason both indication relays NKR and RKR are energized or both are deenergized, or if when the lever is in the reverse position relay NKR is energized and relay RKR is deenergized, the circuit of the winding of the reverse indication magnet RMA cannot be completed and this magnet will prevent movement of 60 lever L away from the reverse position. 65

From the foregoing it is clear, therefore, that the modification shown in Fig. 3 of the drawings is arranged so that preliminary agreement is required between the position of the switch W and the control lever L or movement of the lever L 70 away from either its normal or reverse position is prevented.

Furthermore, the modification shown in Fig. 3 of the drawings requires proper operation of the indication relays NKR and RKR before the lever 75

L may be moved from either the normal or the reverse position.

In Fig. 4 of the drawings there is shown a modification similar to that shown in Fig. 3 in that the normal and reverse indication magnets NMB and RMB perform the functions performed by the lock magnet DM in the system shown in Fig. 1 of the drawings. The system shown in Fig. 4 of the drawings employs segments associated with the indication magnets RMB and NMB of the same type employed in the system shown in Fig. 3 of the drawings.

The modification shown in Fig. 4 differs from that shown in Fig. 3, however, in that the system shown in Fig. 4 does not incorporate the preliminary agreement feature of the system shown in Fig. 3, that is, the modification shown in Fig. 4 does not require agreement between the position of the lever L and of the switch W to permit energization of the indication magnets and thus permit movement of the lever L away from either the normal or the reverse position.

The system shown in Fig. 4 of the drawings is the same as that shown in Fig. 1 of the drawings except as hereinafter explained in detail.

The system shown in Fig. 4 of the drawings includes circuits controlled by contacts B and D associated with the lever L for energizing the normal and reverse indication magnets NMB and RMB. These circuits are similar to the corresponding circuits of the system shown in Fig. 1 of the drawings and may be established when the contacts of the stick relay S are picked up. These circuits provide means to energize the indication magnets to permit movement of the lever L from an intermediate position to the normal or reverse position.

The system shown in Fig. 4 of the drawings includes, in addition, circuits controlled by contacts associated with the lever L and by the latch contacts as well as by contacts of the locking or route relays, not shown, for energizing the indication magnets. These circuits provide means for energizing the indication magnets to permit movement of the lever L away from either the normal or the reverse position.

Referring to the drawings, it will be seen that the modification shown in Fig. 4 has a wire 81b leading from one terminal of a source of current. The circuit of this wire is controlled by contacts of route or locking relays, not shown, so that the circuit of the wire can be completed only when it is safe to effect movement of the switch W between its positions. The circuit is also controlled by the latch contacts 8c and 9c, while connection from wire 81b to one terminal of the winding of the normal indication magnet NMB is controlled by a contact NX associated with the lever L. In addition, connection from latch contact 8c to one terminal of the winding of the reverse indication magnet RMB is controlled by contact RY associated with the lever L.

When the lever L is in the normal position, contact NX is closed, and if the latch contacts 8c and 9c are now closed, a circuit will be established to energize the normal indication magnet NMB, providing the contacts of the route and locking relays, not shown, are picked up. On this energization of the normal indication magnet NMB, the magnet operates to permit movement of the lever L away from the normal position.

When the lever L has been moved away from the normal position beyond point X, contact NX becomes open, but by this time the lever will

have been moved far enough so that its further movement will not be interfered with by the normal indication magnet NMB.

When the lever L is in the reverse position, contact RY is closed so that on closing of the latch contacts 8c and 9c, a circuit is established to energize the winding of reverse indication magnet RMB, provided the contacts of the locking or route relays, not shown, controlling the wire 81b are picked up.

On energization of the reverse indication magnet RMB, the lever L may be moved away from the reverse position R, while on movement of the lever beyond the position Y, contact RY becomes open to interrupt the circuit of the winding of the reverse indication magnet. However, before this circuit is interrupted the lever will have been moved far enough so that further movement of the lever will not be interfered with by the reverse indication magnet.

It will be seen that in the system shown in Fig. 4 of the drawings if the contacts of the locking or route relays associated with wire 81b are open, neither of the indication magnets can be energized and hence the lever L cannot be moved away from either its normal or reverse position.

In this system, therefore, the indication magnets perform the function performed by the lock magnet DM employed in the system shown in Fig. 1 of the drawings.

Although I have herein shown and described one embodiment of the improved switch control and indication system provided by my invention, together with three modifications thereof which I may employ, it should be understood that the invention is not limited to these details of construction, and that numerous changes and modifications may be made therein within the scope of the appended claims without departing from the spirit and scope of my invention.

Having thus described my invention, what I claim is:

1. In combination, a railway track switch, a motor for moving said switch between a normal and a reverse position, a normal and a reverse indication relay, a lever movable between a normal and a reverse position, said lever also having a normal indication position in which it effects operation of the motor to move the switch to the normal position and having a reverse indication position in which it effects operation of the motor to move the switch to the reverse position, a member movable in accordance with movement of the switch, said member being operable when and only when the switch is in the normal position to establish a circuit for energizing the normal indication relay and being operable when and only when the switch is in the reverse position to establish a circuit for energizing the reverse indication relay, a stick relay, a pick-up circuit for said stick relay which is complete when and only when both of the indication relays are deenergized, a stick circuit for said stick relay, said stick circuit being established on picking up of the contacts of the stick relay, a normal indication magnet operable when deenergized to prevent movement of the lever to the normal position, said magnet being operable when energized to permit such lever movement, a reverse indication magnet operable when deenergized to prevent movement of the lever to the reverse position, said magnet being operable when energized to permit such lever movement, and circuits controlled by the lever, by contacts of the

stick relay, and by contacts of the indication relays for energizing said indication magnets.

2. In combination, a railway track switch, a motor for moving said switch between a normal and a reverse position, a normal and a reverse indication relay, a lever movable between a normal and a reverse position, said lever also having a normal indication position in which it effects operation of the motor to move the switch to the normal position and having a reverse indication position in which it effects operation of the motor to move the switch to the reverse position, a member movable in accordance with movement of the switch, said member being operable when and only when the switch is in the normal position to establish a circuit for energizing the normal indication relay and being operable when and only when the switch is in the reverse position to establish a circuit for energizing the reverse indication relay, a stick relay, a pick-up circuit for said stick relay which is complete when and only when both of the indication relays are deenergized, a stick circuit for said stick relay, said stick circuit being established on picking up of the contacts of the stick relay, said lever being operable on movement to either its normal or reverse position to interrupt said stick circuit, a normal indication magnet operable when deenergized to prevent movement of the lever to the normal position, said magnet being operable when energized to permit such lever movement, a reverse indication magnet operable when deenergized to prevent movement of the lever to the reverse position, said magnet being operable when energized to permit such lever movement, and circuits controlled by the lever, by contacts of the stick relay, and by contacts of the indication relays for energizing said indication magnets.

3. In combination, a railway track switch, a motor for moving said switch between a normal and a reverse position, a normal and a reverse indication relay, a lever movable between a normal and a reverse position, said lever also having a normal indication position in which it effects operation of the motor to move the switch to the normal position and having a reverse indication position in which it effects operation of the motor to move the switch to the reverse position, a member movable in accordance with movement of the switch, said member being operable when and only when the switch is in the normal position to establish a circuit for energizing the normal indication relay and being operable when and only when the switch is in the reverse position to establish a circuit for energizing the reverse indication relay, a stick relay, a pick-up circuit for said stick relay which is complete when and only when both of the indication relays are deenergized, a stick circuit for said stick relay, said stick circuit being established on picking up of the contacts of the stick relays, a normal indication magnet operable when deenergized to prevent movement of the lever to the normal position, said magnet being operable when energized to permit such lever movement, a reverse indication magnet operable when deenergized to prevent movement of the lever to the reverse position, said magnet being operable when energized to permit such lever movement, a circuit controlled by said lever for energizing the normal indication magnet, said circuit being complete only when the normal indication relay and the stick relay are energized and the reverse indication relay is deenergized, and a circuit con-

trolled by said lever for energizing the reverse indication magnet, said circuit being complete only when the reverse indication relay and the stick relay are energized and the normal indication relay is deenergized. 5

4. In combination, a railway track switch, a motor for moving said switch between a normal and a reverse position, a normal and a reverse indication relay, a lever movable between a normal and a reverse position, said lever also having a normal indication position in which it effects operation of the motor to move the switch to the normal position and having a reverse indication position in which it effects operation of the motor to move the switch to the reverse position, a member movable in accordance with movement of the switch, said member being operable when and only when the switch is in the normal position to establish a circuit for energizing the normal indication relay and being operable when and only when the switch is in the reverse position to establish a circuit for energizing the reverse indication relay, a stick relay, a pick-up circuit for said stick relay which is complete when and only when both of the indication relays are deenergized, a stick circuit for said stick relay, said stick circuit being established on picking up of the contacts of the stick relay, said lever being operable on movement to either its normal or its reverse position to interrupt said stick circuit, a normal indication magnet operable when deenergized to prevent movement of the lever to the normal position, said magnet being operable when energized to permit such lever movement, a reverse indication magnet operable when deenergized to prevent movement of the lever to the reverse position, said magnet being operable when energized to permit such lever movement, a circuit controlled by said lever for energizing the normal indication magnet, said circuit being complete only when the normal indication relay and the stick relay are energized and the reverse indication relay is deenergized, and a circuit controlled by said lever for energizing the reverse indication magnet, said circuit being complete only when the reverse indication relay and the stick relay are energized and the normal indication relay is deenergized. 10 20 25 30 35 40 45 50 55 60 65 70 75

5. In combination, a railway track switch, a motor for moving said switch between a normal and a reverse position, a normal and a reverse indication relay, a control lever movable between a normal and a reverse position, said lever also having a normal indication position in which it effects operation of the motor to move the switch to the normal position and having a reverse indication position in which it effects operation of the motor to move the switch to the reverse position, a member movable in accordance with movement of the switch, said member being operable when and only when the switch is in the normal position to establish a circuit to energize the normal indication relay and being operable when and only when the switch is in the reverse position to establish a circuit to energize the reverse indication relay, a stick relay, means operable only during movement of the switch between its two positions for establishing a pick-up circuit for said stick relay, said stick relay being operable when energized to establish a stick circuit for energizing its own winding, a normal indication magnet operable when deenergized to prevent movement of the lever to the normal position, said magnet being operable when energized to permit such lever movement, a reverse indication mag- 10 15 20 25 30 35 40 45 50 55 60 65 70 75

net operable when deenergized to prevent movement of the lever to the reverse position, said magnet being operable when energized to permit such lever movement, and circuits controlled by contacts of the stick relay, by contacts of the indication relays, and by contacts associated with the lever for energizing said indication magnets.

6. In combination, a railway track switch, a motor for moving said switch between a normal and a reverse position, a normal and a reverse indication relay, a control lever movable between a normal and a reverse position, said lever also having a normal indication position in which it effects operation of the motor to move the switch to the normal position and having a reverse indication position in which it effects operation of the motor to move the switch to the reverse position, a member movable in accordance with movement of the switch, said member being operable when and only when the switch is in the normal position to establish a circuit to energize the normal indication relay and being operable when and only when the switch is in the reverse position to establish a circuit to energize the reverse indication relay, a stick relay, means operable only during movement of the switch between its two positions for establishing a pick-up circuit for said stick relay, said stick relay being operable when energized to establish a stick circuit for energizing its own winding, said lever being operable on movement to either its normal or reverse position to interrupt said stick circuit, a normal indication magnet operable when deenergized to prevent movement of the lever to the normal position, said magnet being operable when energized to permit such lever movement, a reverse indication magnet operable when deenergized to prevent movement of the lever to the reverse position, said magnet being operable when energized to permit such lever movement, and circuits controlled by contacts of the stick relay, by contacts of the indication relays, and by contacts associated with the lever for energizing said indication magnets.

7. In combination, a railway track switch, a motor for moving said switch between a normal and a reverse position, a normal and a reverse indication relay, a lever movable between a normal and a reverse position, said lever also having a normal indication position in which it effects operation of the motor to move the switch to the normal position and having a reverse indication position in which it effects operation of the motor to move the switch to the reverse position, a member movable in accordance with movement of the switch, said member being operable when and only when the switch is in the normal position to establish a circuit for energizing the normal indication relay and being operable when and only when the switch is in the reverse position to establish a circuit for energizing the reverse indication relay, a stick relay, a pick-up circuit for said stick relay which is complete when and only when both of the indication relays are deenergized, a stick circuit for said stick relay, said stick circuit being established on picking up of the contacts of the stick relay, a normal indication magnet operable when deenergized to prevent movement of the lever to the normal position, said magnet being operable when energized to permit such lever movement, a reverse indication magnet operable when deenergized to prevent movement of the lever to the reverse position, said magnet being operable when energized to permit such lever movement, circuits controlled by contacts of the stick relay, by contacts of the indication relays, and by contacts associated with the lever for energizing said indication magnets.

by the lever, by contacts of the stick relay, and by contacts of the indication relays for energizing said indication magnets, a lock magnet operable when deenergized to prevent movement of the lever away from either its normal or reverse position to either of its indication positions, said lock magnet being operable when energized to permit such lever movement, and a circuit controlled by the lever and also by the indication relays for energizing said lock magnet. 5

8. In combination, a railway track switch, a motor for moving said switch between a normal and a reverse position, a normal and a reverse indication relay, a lever movable between a normal and a reverse position, said lever also having a normal indication position in which it effects operation of the motor to move the switch to the normal position and having a reverse indication position in which it effects operation of the motor to move the switch to the reverse position, a member movable in accordance with movement of the switch, said member being operable when and only when the switch is in the normal position to establish a circuit for energizing the normal indication relay and being operable when and only when the switch is in the reverse position to establish a circuit for energizing the reverse indication relay, a stick relay, a pick-up circuit for said stick relay which is complete when and only when both of the indication relays are deenergized, a stick circuit for said stick relay, said stick circuit being established on picking up of the contacts of the stick relay, a normal indication magnet operable when deenergized to prevent movement of the lever to the normal position, said magnet being operable when energized to permit such lever movement, a reverse indication magnet operable when deenergized to prevent movement of the lever to the reverse position, said magnet being operable when energized to permit such lever movement, circuits controlled by the lever, by contacts of the stick relay, and by contacts of the indication relays for energizing said indication magnets, a lock magnet operable when deenergized to prevent movement of the lever away from either its normal or reverse position to either of its indication positions, said magnet being operable when energized to permit such lever movement, a circuit for energizing said magnet when the lever is in the normal position, said circuit being complete only when the normal indication relay is energized and the reverse indication relay is deenergized, and a circuit for energizing said magnet when the lever is in the reverse position, said circuit being complete only when the reverse indication relay is energized and the normal indication relay is deenergized. 10

9. In combination, a railway track switch, a motor for moving said switch between a normal and a reverse position, a normal and a reverse indication relay, a lever movable between a normal and a reverse position, said lever also having a normal indication position in which it effects operation of the motor to move the switch to the normal position and having a reverse indication position in which it effects operation of the motor to move the switch to the reverse position, a member movable in accordance with movement of the switch, said member being operable when and only when the switch is in the normal position to establish a circuit for energizing the normal indication relay and being operable when and only when the switch is in the reverse position to establish a circuit for energizing the reverse indication relay, a stick relay, a pick-up circuit for 15

- said stick relay which is complete when and only when both of the indication relays are deenergized, a stick circuit for said stick relay, said stick circuit being established on picking up of the contacts of the stick relay, a normal indication magnet operable when deenergized to prevent movement of the lever to or from the normal position, said magnet being operable when energized to permit such lever movement, a reverse indication magnet operable when deenergized to prevent movement of the lever to or from the reverse position, said magnet being operable when energized to permit such lever movement, a circuit for energizing the normal indication magnet, said circuit being complete when and only when the lever is in the normal indication position, the stick relay and the normal indication relay are energized and the reverse indication relay is deenergized, another circuit for energizing the normal indication magnet, said other circuit being complete only when the lever is in the normal position, the normal indication relay is energized and the reverse indication relay is deenergized, a circuit for energizing the reverse indication magnet, said circuit being complete when and only when the lever is in the reverse indication position, the stick relay and the reverse indication relay are energized, and the normal indication relay is deenergized, and another circuit for energizing the reverse indication magnet, said circuit being complete only when the lever is in the reverse position, the reverse indication relay is energized and the normal indication relay is deenergized.
10. In combination, a railway track switch, a motor for moving said switch between a normal and a reverse position, a normal and a reverse indication relay, a lever movable between a normal and a reverse position, said lever also having a normal indication position in which it effects operation of the motor to move the switch to the normal position and having a reverse indication position in which it effects operation of the motor to move the switch to the reverse position, a member movable in accordance with movement of the switch, said member being operable when and only when the switch is in the normal position to establish a circuit for energizing the normal indication relay and being operable when and only when the switch is in the reverse position to establish a circuit for energizing the reverse indication relay, a stick relay, a pick-up circuit for said stick relay which is complete when and only when both of the indication relays are deenergized, a stick circuit for said stick relay, said stick circuit being established on picking up of the contacts of the stick relay, a normal indication magnet operable when deenergized to prevent movement of the lever to or from the normal position, said magnet being operable when energized to permit such lever movement, a reverse indication magnet operable when deenergized to prevent movement of the lever to or from the reverse position, said magnet being operable when energized to permit such lever movement, a circuit through which current may be supplied to energize the normal indication magnet provided the stick relay is energized and the lever is in the normal indication position, another circuit independent of the stick relay and through which current may be supplied to energize the normal indication magnet when the lever is in the normal position provided the normal indication relay is energized and the reverse indication relay is deenergized, a circuit through which current may be supplied to energize the reverse indication magnet provided the stick relay is energized and the lever is in the reverse indication position, and another circuit independent of the stick relay and through which current may be supplied to energize the reverse indication magnet when the lever is in the reverse position provided the reverse indication relay is energized and the normal indication relay is deenergized.
11. In combination, a railway track switch, a motor for moving said switch between a normal and a reverse position, a lever movable between a normal and a reverse position, said lever also having a normal indication position in which it effects operation of the motor to move the switch to the normal position and having a reverse indication position in which it effects operation of the motor to move the switch to the reverse position, a normal indication magnet operable when deenergized to prevent movement of the lever to or from the normal position, said magnet being operable when energized to permit such lever movement, a reverse indication magnet operable when deenergized to prevent movement of the lever to or from the reverse position, said magnet being operable when energized to permit such lever movement, a stick relay, a pick-up circuit for said stick relay which is complete when and only when both of the indication relays are deenergized, a stick circuit for said stick relay, said stick circuit being established on picking up of the contacts of the stick relay, a normal indication magnet operable when deenergized to prevent movement of the lever to or from the normal position, said magnet being operable when energized to permit such lever movement, a reverse indication magnet operable when deenergized to prevent movement of the lever to or from the reverse position, said magnet being operable when energized to permit such lever movement, a circuit through which current may be supplied to energize the normal indication magnet when the lever is in the normal position provided the normal indication relay is energized and the reverse indication relay is deenergized, a circuit through which current may be supplied to energize the reverse indication magnet when the lever is in the reverse position provided the reverse indication relay is energized and the normal indication relay is deenergized.
12. In combination, a railway track switch, a motor for moving said switch between a normal and a reverse position, a lever movable between a normal and a reverse position, said lever also having a normal indication position in which it effects operation of the motor to move the switch to the normal position and having a reverse indication position in which it effects operation of the motor to move the switch to the reverse position, a normal indication magnet operable when deenergized to prevent movement of the lever to or from the normal position, said magnet being operable when energized to permit such lever movement, a reverse indication magnet operable when deenergized to prevent movement of the lever to or from the reverse position, said magnet being operable when energized to permit such lever movement, a stick relay, means operable only during movement of the switch from one of its positions to the other to effect energization of the stick relay, the stick relay when energized estab-

lishing a stick circuit through which current may be supplied to maintain itself energized, the lever being operable in either its normal or its reverse position to interrupt said stick circuit, a circuit 5 for supplying current to energize the normal indication magnet, said circuit being complete only when the lever is in the normal indication position and the stick relay is energized, means responsive to the position of the switch for also controlling said last-named circuit, said means being operable to establish said circuit only when the switch is in the normal position, a circuit for supplying current to energize the reverse indication magnet, said circuit being complete only when the lever is in the reverse indication position and the stick relay is energized, and means responsive to the position of the switch for also controlling said last-named circuit, said means being operable to establish said circuit only when the switch is in the reverse position.

13. In combination, a railway track switch, a motor for moving said switch between a normal and a reverse position, a control lever movable between a normal and a reverse position, said control lever also having a normal indication position in which it effects operation of the motor to move the switch to the normal position and a reverse indication position in which it effects operation of the motor to move the switch to the reverse position, a normal indication magnet operable when deenergized to prevent movement of the control lever from the normal indication position to the normal position, said magnet being operable when energized to permit such lever movement, a reverse indication magnet operable when deenergized to prevent movement of the control lever from the reverse indication position to the reverse position, said magnet being operable when energized to permit such lever movement, a normal supply circuit for energizing the normal indication magnet and a reverse supply circuit for energizing the reverse indication magnet, a stick relay having contacts controlling said normal and reverse supply circuits, said stick relay contacts also controlling a stick circuit for energizing its own winding, said stick relay contacts being operable to permit said circuits to be completed when and only when the relay winding is energized, means operable when and only when the switch is in transit between its two positions to establish a pick-up circuit for the stick relay, contacts controlled by said lever for controlling said supply circuits and said stick circuit, said contacts being operable to interrupt said circuits when the lever is in either its normal or its reverse position and being operable to permit said stick circuit to be completed when the lever is in either of its indication positions, said contacts being also operable when and only when the lever is in the normal indication position to permit the normal supply circuit to be completed and being operable when and only when the lever is in the reverse indication position to permit the reverse supply circuit to be completed, a normal and a reverse indication relay, means governed by the switch for energizing said indication relays, said means being operable when and only when the switch is in the normal position to energize the normal indication relay and being operable when and only when the switch is in the reverse position to energize the reverse indication relay, the indication relays controlling said supply circuits in such manner that the normal supply circuit is complete only when the normal indication relay is energized and the reverse indication relay is deenergized, and so that the reverse supply circuit is complete only when the reverse indication relay is energized and the normal indication relay is deenergized.

14. In combination, a railway track switch, a motor for moving said switch between a normal and a reverse position, a control lever movable

between a normal and a reverse position, said control lever also having a normal indication position in which it effects operation of the motor to move the switch to the normal position and a reverse indication position in which it effects operation of the motor to move the switch to the reverse position, a normal indication magnet operable when deenergized to prevent movement of the control lever from the normal indication position to the normal position, said magnet being operable when energized to permit such lever movement, a reverse indication magnet operable when deenergized to prevent movement of the control lever from the reverse indication position to the reverse position, said magnet being operable when energized to permit such lever movement, a normal supply circuit for energizing the normal indication magnet and a reverse supply circuit for energizing the reverse indication magnet, a stick relay having contacts controlling said normal and reverse supply circuits, said stick relay contacts also controlling a stick circuit for energizing its own winding, said stick relay contacts being operable to permit said circuits to be completed when and only when the relay winding is energized, means operable when and only when the switch is in transit between its two positions to establish a pick-up circuit for the stick relay, contacts controlled by said lever for controlling said supply circuits and said stick circuit, said contacts being operable to interrupt said circuits when the lever is in either its normal or its reverse position and being operable to permit said stick circuit to be completed when the lever is in either of its indication positions, said contacts being also operable when and only when the lever is in the normal indication position to permit the normal supply circuit to be completed and being operable when and only when the lever is in the reverse indication position to permit the reverse supply circuit to be completed, a normal and a reverse indication relay, means governed by the switch for energizing said indication relays, said means being operable when and only when the switch is in the normal position to energize the normal indication relay and being operable when and only when the switch is in the reverse position to energize the reverse indication relay, the indication relays controlling said supply circuits in such manner that the normal supply circuit is complete only when the normal indication relay is energized and the reverse indication relay is deenergized, and so that the reverse supply circuit is complete only when the reverse indication relay is energized and the normal indication relay is deenergized.

15. In an interlocking machine, in combination, a railway track switch, a motor for moving said switch between a normal and a reverse position, a control lever movable between a normal and a reverse position, said control lever also having a normal indication position in which it effects operation of the motor to move the switch to the normal position and a reverse indication position in which it effects operation of the motor to move the switch to the reverse position, a normal indication magnet operable when deenergized to prevent movement of the control lever from the normal indication position to the normal position, said magnet being operable when energized to permit such lever movement, a reverse indication magnet operable when deenergized to prevent movement of the control lever from the reverse indication position to the reverse position, said magnet being operable when energized to 70

permit such lever movement, a normal supply circuit for energizing the normal indication magnet and a reverse supply circuit for energizing the reverse indication magnet, means operable 5 when and only when the switch is in transit between its two positions and the control lever is in either of its indication positions to establish connections to permit the supply circuits to be completed and to maintain such connections until the control lever is moved to either its normal or reverse position, contacts associated with the control lever and controlling said supply circuits, said contacts being operable when and only when the lever is in 10 the normal indication position to permit the normal supply circuit to be completed and being operable when and only when the lever is in the reverse indication position to permit the reverse supply circuit to be completed, and means governed 15 by the switch for also controlling said supply circuits, said means being operable to permit completion of the normal supply circuit only when the switch is in the normal position and being operable to permit completion of the reverse supply circuit only when the switch is in the reverse position.

16. In an interlocking machine, in combination, a railway track switch, a motor for moving said switch between a normal and a reverse position, 20 a control lever movable between a normal and a reverse position, said control lever also having a normal indication position in which it effects operation of the motor to move the switch to the normal position and a reverse indication position 25 in which it effects operation of the motor to move the switch to the reverse position, a normal indication magnet operable when deenergized to prevent movement of the control lever from the normal indication position to the normal position, said magnet being operable when energized

to permit such lever movement, a reverse indication magnet operable when deenergized to prevent movement of the control lever from the reverse indication position to the reverse position, said magnet being operable when energized to 5 permit such lever movement, a normal supply circuit for energizing the normal indication magnet and a reverse supply circuit for energizing the reverse indication magnet, means operable when and only when the switch is in transit between its two positions and the control lever is in either of its indication positions to establish connections to permit the supply circuits to be completed and to maintain such connections until the control lever is moved to either its normal or 10 reverse position, contacts associated with the control lever and controlling said supply circuits, said contacts being operable when and only when the lever is in the normal indication position to permit the normal supply circuit to be completed 15 and being operable when and only when the lever is in the reverse indication position to permit the reverse supply circuit to be completed, a normal and a reverse indication relay, means governed 20 by the switch for energizing said indication relays, said means being operable when and only when the switch is in the normal position to energize the normal indication relay and being operable when and only when the switch is in the reverse position to energize the reverse indication relay, the indication relays controlling said 25 supply circuits in such manner that the normal supply circuit is complete only when the normal indication relay is energized and the reverse indication relay is deenergized, and so that the reverse supply circuit is complete only when the reverse indication relay is energized and the normal indication relay is deenergized.

HENRY S. YOUNG. 40
